(57) CLAIM

The ornamental design for a smoking article holder, as shown and described.

DESCRIPTION

FIG. 1 is a top perspective view of a smoking article holder embodying my new design;

FIG. 2 is a top perspective view of the smoking article holder of FIG. 1 in an open position;

FIG. 3 is a bottom perspective view of the smoking article holder of FIG. 1;

FIG. 4 is a bottom perspective view of the smoking article holder of FIG. 1 showing environment;

FIG. 5 is a left-side view of the smoking article holder of FIG. 1;

FIG. 6 is a right-side view of the smoking article holder of FIG. 1;

FIG. 7 is a top view of the smoking article holder of FIG. 1;

FIG. 8 is a bottom view of the smoking article holder of FIG. 1;

FIG. 9 is a front view of the smoking article holder of FIG. 1; and,

FIG. 10 is a rear view of the smoking article holder of FIG. 1.

The broken lines show portions of the smoking article holder that form no part of the claimed design.
